UNITED STATES PATENT OFFICE.

FRIEND J. BRINGHAM, OF SAN FRANCISCO, CALIFORNIA, ASSIGNOR TO THE
SEAMLESS LEATHER COMPANY, OF CHICAGO, ILLINOIS.

MACHINE FOR MAKING LEATHER LOOPS.

SPECIFICATION forming part of Letters Patent No. 534,465, dated February 19, 1895.

Application filed August 1, 1893. Serial No. 482,101. (No model.)

To all whom it may concern:

Be it known that I, FRIEND J. BRINGHAM, a citizen of the United States, residing at San Francisco, in the county of San Francisco and State of California, have invented certain new and useful Improvements in Machines for Making Leather Loops, &c.; and I do hereby declare that the following is a full, clear, and exact description thereof.

10 My invention relates to apparatus for making endless leather loops and more particularly to the loops described in my Patent No. 500,111, granted June 27, 1893.

15 The object of the invention is to provide a machine, or machines, which shall, first, form a blank by slitting a piece of leather edge-wise and cutting it off near the ends of the slit so as to form a slitted endless blank to be afterward finished and completed into a perfect loop; secondly, to provide a machine which will take a long strip of leather, and, as it is fed into the machine will slit it edge-wise and cut it off successively into proper lengths to be afterward completed to form the finished loop.

25 Such a machine is illustrated in the accompanying drawings, in which—

Figure 1, is a side elevation; Fig. 2, a front view; Fig. 3, a half section in perspective of the male finishing die; Fig. 4, a like view of the female finishing die; Fig. 5, a separate view of the blank for a loop before finishing; Fig. 6, a view of a completed loop. Fig. 7, is a perspective view of the spring attached to the movable jaw of the machine.

35 The machine shown in the drawings is provided with interchangeable mechanism for making and for finishing the loops. It should be understood however that the making and finishing of the loops although they form parts of one complete process, may be done on separate machines; and also, that separate machines may be used for making and finishing different sizes and styles of loops, 40 and also that one machine may be provided with adjustable or interchangeable mechanism for making all sizes and styles of loops.

45 Referring to the drawings, A represents a table which supports the operative parts of the machine.

50 B, is a standard on the table in the upper

end of which is pivoted the beam C, from which a connecting rod D, extends to the treadle K. In a slot 1, of the beam is hung a rod E, which works vertically in guides 2, 55 forming part of the standard B. Below the guides and removably secured to the rod E, by a set screw 3, is a cutter head 4, in which is set the central dividing knife blade F, and the cutting knives 5 and 6, one upon each 60 side of and at right angles to the blade F. The knives derive a simultaneous vertical reciprocation from the movement of the treadle and its connections. The distance between the knives 5, and 6, is the length of the loop 65 (Fig. 6) before finishing, and the knife F, projects a little below them as shown. These three blades acting together, divide the leather edge-wise, and at the same time cut it off near the ends of the division, so as to form 70 the unfinished loop blank shown in Fig. 6.

The leather, whether a continuous strip or a single piece, is held during the operation of dividing and cutting, by mechanism upon the table, best illustrated in Fig. 2. A removable 75 throat plate 7, is dovetailed into the table and is slotted to permit the passage of each knife (dotted lines, Fig. 2). An adjustable jaw 8, the base 9, of which moves in guides 10, (Fig. 1) is moved by a nut 11, on the screw shank 80 12, which works in standards 13, on the table. This jaw is intended to be adjusted toward or from the throat plate according to the thickness of the leather. A movable jaw 14, slides in similar guides upon the table at the opposite side of the throat plate, the shank 15 of which is surrounded by a spring 16, which tends to keep it constantly away from the throat plate. This rod is actuated by a pivoted bell crank 17, connected to the treadle 90 lever by a connecting rod 18, at a point which will give the limited movement required. The downward motion of the treadle will thus depress the knives and at the same time move the jaw 14, inward against the pressure of the 95 spring. The operator now feeds the leather, edge up, over the throat plate and depresses the treadle. Before the knives have reached the leather, it is clamped between the jaws, and firmly held on the throat plate until the 100 treadle is released. The center knife divides the leather edge-wise while the side knives cut

it off near the ends of the division. A strip of leather may thus be very rapidly cut into unfinished loop blanks (Fig. 5) each blank as it is separated, being pushed out of the way by the end of the strip following it. Small leather scraps are, of course, fed in separately.

With such a machine as is here described to illustrate the process, the work of making the unfinished loops will be continued until a sufficient number have been produced ready for finishing; and then, by the use of the interchangeable finishing mechanism, the whole quantity of loops will be successively finished. To accomplish this, with this machine, the cutter head and knives, the jaws, and the throat plate are all removed, and the compressing and finishing dies H, I, substituted for them.

Fig. 4, represents a female die H, having a base formed so as to dovetail into the place before occupied by the throat plate. The interior shape of this die is that of a completed loop, so that the insertion of the unfinished loop within it will cause it to open out slightly.

In place of the cutter head is secured to the rod E the male die I, (Fig. 3). The depression of the treadle now brings down the die I, and the blank is fully opened out and compressed into the shape shown in Fig. 6, which represents an endless and seamless leather loop, ready for attachment as a billet loop, or box loop, or slide loop, as the case may be, and of superior strength and durability to the stitched loop now in use.

It is better to secure to the jaw 14, a spring 20, such as that shown in Fig. 7, which bears upon the leather and holds it before the two jaws come together, and is forced back against the jaw or into a recess formed in it when the two jaws are closed.

The machine shown in the drawings is capable of modification to some extent. For in-

stance, duplicate knives can be used operating toward one another. The knives can move horizontally instead of vertically; and of course power of any kind can be employed for operating the machine instead of the treadle shown. The loops produced by this method, can thus not only be made with great rapidity from leather strips, but can also be made from leather scraps and waste which are ordinarily useless; and, as the process is purely mechanical and the machinery for carrying it out automatic in action, the skilled labor now required for cutting out and sewing the loops can be dispensed with, while the loops are made far more rapidly, and are of superior quality.

What I claim is—

1. A machine for making endless leather loops comprising a reciprocating cross head, with means for operating the same, a knife F for slitting the leather, and a second knife arranged at right angles to the first knife and at a distance therefrom to cut off the slitted piece, substantially as described.

2. In a machine for making endless leather loops, a reciprocating head, a slitting knife carried thereby and a trimming knife arranged at right angles thereto, a distance therefrom and centrally of the slitting knife whereby the leather is slit and the slitted portion is cut off leaving an uncut portion between the slit and the cut end of the leather, substantially as described.

In testimony whereof I have affixed my signature, in presence of two witnesses, this 19th day of July, 1893.

FRIEND J. BRINGHAM.
